ERNEST O. PATZ, OF SCARSDALE, NEW YORK

PICKING MACHINE

Application filed December 13, 1927. Serial No. 239,639.

My invention relates to a new and improved picking machine.

One of the objects of my invention is to provide a machine for tearing or stripping 5 rags so as to preserve the threads or fibres in their original length.

Another object of my invention is to provide a machine for this purpose which shall require much less power than machines here- 10 tofore used.

Another object of my invention is to provide a machine which will improve the old type garnetting machine so as to separate 15 the light stripped fibres from the heavier portion of the rags.

Other objects of my invention will be set forth in the following description and drawings which illustrate a preferred embodiment thereof, it being understood that the 20 above general statement of the objects of my invention is intended merely to generally explain the same and not to limit in any manner.

Fig. 1 is a plan view of the improved machine.

Fig. 2 is a front elevation.

Fig. 3 is an end elevation.

Fig. 4 is a rear elevation.

Figs. 5 and 6 are elevations of different types of picking rollers.

Fig. 7 is a detail elevation showing the feed belt.

Figs. 8 and 9 are respectively sectional views on the lines 8-8 and 9-9 of Fig. 5 and of Fig. 6.

Fig. 10 is a detail side elevation.

The pulley 1 is connected by means of a belt or the like to a suitable motor drive. A pulley 2 is on the same shaft as pulley 1 and it is connected by means of a belt to either 40 tight pulley 3 or loose pulley 3^a upon the shaft 3'. An ordinary belt shifter S shifts the belts from one of the pulleys 3 or 3^a to the other. The pulley 4 upon the shaft 3' is connected by means of a suitable belt to the pulley 5 upon whose shaft the gear 6 is mounted. The gear 6 meshes with a drive gear 7 upon whose shaft sprocket 8 is mounted. The sprocket 8 is connected to sprocket 9 by means of a suitable chain. The top roller R is upon the same shaft as sprocket 9. The top roller

R is made of any suitable material and it is covered with hard rubber and it is downwardly forced by the spring S' so as to be tightly pressed against the bottom roller R', which is of similar construction. The shaft 55 of the pulley 5 also has a sprocket 10 which is connected by a suitable chain to sprocket 11 upon whose shaft the bottom roller R' is mounted. The shaft of the sprocket 11 also has a gear 12 which meshes with intermediate gear 13, which meshes with gear 14. An endless feed track 15 passes at one end about a roller 16 which is upon the same shaft as gear 14. The other end of the endless feed track 15 passes around a stationary member 16' of the shape shown in Fig. 7.

The picking cylinder 20 having the teeth 21, is mounted upon the shaft of the pulley 1. In the embodiment shown in Fig. 8 the teeth 21 are inclined to the picking cylinder 20, whereas in the embodiment shown in Fig. 6 said teeth 21 are radially directed.

The operation of the device is as follows:—

The rags to be picked are placed upon the front of the endless feed track 15 and they are fed forward between the rollers R and R', which are both positively driven. The rags are compressed between the rollers R and R', which also feed them forwardly so that they are caught by the teeth 21 of the 75 picking cylinder 20. Since the picking cylinder 20 is revolved at very high velocity it produces a strong air current, like a centrifugal air blower. Hence, the relatively light fibres which are stripped from the rags are carried around by the air current thus produced so that they move downwardly upon the adjustable slide 30 into the outlet conduit 32. The heavier pieces of rag are thrown over the top of the adjustable slide 30 into the collecting box 31 from which they can be readily removed.

As shown in Figs. 1 and 2, the teeth of the picking cylinder 20 are closely adjacent rollers R and R'. Since the circumferential speed of the teeth 21 is much higher than the circumferential speed of the rollers R and R', the said teeth 21 exert a rapid picking action upon the rags, thus rapidly stripping off the fibres. Likewise, and as clearly shown in Fig. 100

7 the top of the picking roller 20 is above the top of the roller R. Hence, the material which is removed from the rags by the picking cylinder 20 is thrown upwardly and away from rollers R and R', so that the heavy portions of said rags are thrown above the top of the adjustable slide 30 into the collecting box. As a rag is fed forwardly by the rollers R and R', it is subjected to the stripping action of the teeth 21, before the rear end of the rag is released by the rollers R and R'. The light fibres which are stripped from a rag are also thrown towards the collecting box 31, but these fibres are so light that they do not pass over the top of the adjustable slide 30, so that said light fibres are separated and can be removed through the outlet 32. The members 31 and 32 may be considered in effect as being separate chambers. The stripping means 20 first strips the stripped fibres and then throws the heavier residue of the rags away from the feed rollers R and R', and the resistance of the atmosphere automatically separates the said stripped fibres from the heavier portions 25 of the rags. It will be noted that the collecting chamber 32 is below the stripping cylinder 20 so that by merely adjusting the slide 30 provided at the inlet end of said chamber 32, the lighter fibres of the material can be separated from the heavier residues thereof. Likewise, the collecting chamber 31 for the heavier residues is in line with the circumferential movement of the stripping cylinder 20 so that the heavier residues are thrown directly into said collecting chamber 31.

I have shown a preferred embodiment of my invention, but it is clear that numerous changes and omissions could be made without departing from its spirit.

40 I claim:—

1. A picking machine comprising a picking cylinder having teeth, means adapted to feed material to the said picking cylinder so that the said picking cylinder operates to pick the fibres from the material, means adapted to revolve said picking cylinder with sufficient velocity so that the fibres are thrown away from said teeth, said picking cylinder also operating to throw the heavier residues of said material away from the said feeding means, a first collecting chamber for the lighter material located underneath the said picking cylinder, said collecting chamber having an adjustable slide at the inlet 45 thereof, said adjustable slide being located behind the said picking cylinder, and a second chamber for collecting the said heavier residues, the said slide being between said picking cylinder and the inlet to said second chamber.

2. A picking machine comprising a picking cylinder having teeth, means adapted to feed material to said picking cylinder so that said picking cylinder operates to pick fibres from the material, means adapted to revolve said

70 picking cylinder with sufficient velocity so that the fibres are thrown away from said teeth, said picking cylinder also operating to throw the heavier residues away from said feeding means, a partition located sufficiently close to said picking cylinder so that the picking cylinder can throw only the heavier residues directly over the top of said partition, said partition having no part thereof extending above the top of said cylinder and said cylinder being revolved so that the part thereof which is adjacent said partition moves downwardly, a first collecting chamber for the heavier residues having said partition located in its inlet so that the heavier residues thrown over the top of said partition directly enter said first collecting chamber, and a second collecting chamber located below said first collecting chamber and adapted to receive the fibres deflected by the partition.

75 3. A picking machine comprising a picking cylinder having teeth, means adapted to feed material to said picking cylinder so that said picking cylinder operates to pick fibres from the material, means adapted to revolve said picking cylinder with sufficient velocity so that the fibres are thrown away from said teeth, said picking cylinder also operating to throw the heavier residues away from said feeding means, a partition located sufficiently close to said picking cylinder so that the picking cylinder can throw only the heavier residues directly over the top of said partition, said partition having no part thereof extending above the top of the cylinder and being 80 sufficiently spaced from said cylinder to permit the fibres which are separated from said material and which are thrown away from said teeth to settle below the top of said partition to be deflected thereby, said cylinder 85 being revolved so that the part thereof which is adjacent said partition moves downwardly, a first collecting chamber for the heavier residues having said partition located in its inlet so that the heavier residues thrown over the top of said partition directly enter said first collecting chamber, and a second collecting chamber located below said first collecting chamber and adapted to receive the fibres deflected by the partition.

90 4. A picking machine comprising a picking cylinder having teeth, means adapted to feed material to said picking cylinder so that said picking cylinder operates to pick fibres from the material, means adapted to revolve said picking cylinder with sufficient velocity so that the fibres are thrown away from said teeth, said picking cylinder also operating to throw the heavier residues in the same general direction as said fibres, and a partition 95 sufficiently spaced from said picking cylinder to permit the lighter fibres to settle below the top of said partition while the heavier pieces are thrown over the top of said partition, said picking cylinder being revolved so that the 100 105 110 115 120 125 130

part thereof which is adjacent said partition moves downwardly, a first collecting chamber for the heavier residues having said partition located in its inlet so that the heavier residues thrown over the top of said partition enter said first collecting chamber, and a second collecting chamber located below said first collecting chamber and adapted to receive the fibres which settle below the top of said partition.

10 In testimony whereof I affix my signature.
ERNEST O. PATZ.
